CLAIM

I claim the ornamental design for a drinking straw mountable container, as shown and described.

DESCRIPTION

FIG. 1 is a front perspective view of the new drinking straw mountable container design in an open conformation and mounted on a drinking straw inserted in a beverage serving cup;

FIG. 2 is a rear view of the container in isolation;

FIG. 3 is a front view thereof;

FIG. 4 is a right view thereof;

FIG. 5 is a left view thereof;

FIG. 6 is a top view thereof;

FIG. 7 is a bottom view thereof; and,

FIG. 8 is a front perspective view of the container in a closed conformation.

The broken lines in the drawing are included for the purpose of illustrating unclaimed environment only, and, form no part of the claimed design.

1 Claim, 5 Drawing Sheets
